BLACK-OUT HEAD LAMP

Robert N. Falge, George W. Onksen, Jr., and William R. Goris, Anderson, Ind., assignors to General Motors Corporation, Detroit, Mich., a corporation of Delaware

Application April 29, 1943, Serial No. 485,042

5 Claims. (Cl. 240—48.4)

1

The present invention relates generally to vehicle lamps and more particularly to the construction of a headlamp adapted for use on military or civilian vehicles which must be operated at night in combat or other zones where it is desired to prevent the detection of the vehicles by enemy aircraft.

The principal object of the invention is therefore to provide a headlamp construction which will afford only such illumination of the roadway as has been found necessary for reasonably safe operation of the vehicle and in which all direct rays are adequately shielded to prevent observation thereof from above.

To simplify and facilitate the design and manufacture of the present headlamp it is proposed to utilize a conventional form of reflector such as may be mounted within a standard headlamp casing and obtain the desired light distribution and shielding by the provision of a lens and shield of novel construction.

In the embodiment disclosed herein the shield consists essentially of a metal front cover plate for the lens which is provided with a relatively restricted opening for the passage of light rays with a forwardly projecting hood above this opening and to obtain the desired beam pattern this opening is in the form of a horizontally extending narrow window or slot of irregular contour and the portion of the lens which is exposed through the slot is provided with refracting surfaces as will be hereinafter described.

The several features of the present invention will be apparent from the following description of the embodiment illustrated in the accompanying drawings, in which:

Figure 1 is a vertical section taken substantially on line 1—1 of Figure 2 with parts in elevation of an embodiment of the present invention.

Figure 2 is a front elevation on line 2—2 of Figure 1 with parts broken away.

Figure 3 is a fragmentary rear elevation of the lens taken substantially on line 3—3 of Figure 1.

Figure 4 is an enlarged vertical central section of a portion of the lens and shield.

Figure 5 is an enlarged fragmentary horizontal section of the lens taken substantially on line 5—5 of Figure 4.

Figure 6 is a diagrammatic view showing the beam pattern and the relation of the same to respective portions of the slot in the shield.

Referring first to the showing in Figure 1, the reflector 2, light bulb 4, lens 6 and shield 8 are preferably secured together to constitute a self-contained unit which, as will be understood, is

2

adapted to be mounted within a standard headlamp casing having suitable means to secure and support the same upon a vehicle. The reflector 2 may be of conventional paraboloidal form and is provided with an opening to receive the base 10 of the light bulb 4 which is secured in the reflector as by solder 12 with the bulb filament located at the focal point of the reflector and with the front end of the bulb shielded as indicated at 14 to cut off direct rays from the filament.

The lens 6 may be secured within the open end of the reflector 2 by clamping the marginal portion 16 of the lens between an annular peripheral flange 18 on the shield 8 and an annular seat 20 on the reflector with a sealing gasket 22 of rubber or similar material interposed between the lens and reflector. As shown in Figure 1 the open end of the reflector may be extended forwardly beyond the annular seat 20 and be clinched or spun over the flange 18 of the shield 8 as at 24 to secure the lens and shield to the reflector and also conceal and protect the marginal portion 16 of the lens and the gasket 22. To position the shield circumferentially with reference to the lens, the lens may be formed with spaced recesses in the outer face of the marginal portion 16, as indicated at 26 in Figure 2, to receive correspondingly spaced indentations such as indicated at 28 in Figure 2 on the flange 18 of the shield.

Referring now to the construction of the lens 6 and shield 8 it will first be noted that the shield is provided with a light transmitting opening in the form of a horizontally extending, relatively narrow window slot which is indicated generally at 30. As will be apparent from the showing in Figures 1 and 2, this window slot 30 is located above the longitudinal axis of the reflector, lens and shield assembly, and the shield is provided with a forwardly projecting hood 32 which may be secured as by spot-welding to the shield. The hood 32 is substantially arc-shaped with the front end thereof closed by a vertical wall 34. The lower edges of the hood and the bottom edge of the window slot 30 are in a plane inclined approximately 1° to the horizontal. Therefore the slot is not visible to anyone above this plane.

Before describing the particular contour of the window slot 30 and the refracting surfaces on the lens 6 which are disclosed herein it is desired to call attention to the principal requirements which should be satisfied to obtain the desired illumination and to develop the desired beam pattern. The refracting lens surfaces must, for instance, provide a certain degree of both vertical and hori-

horizontal spread of the light emitted through the relatively narrow horizontal slot 30 and all of the light rays should be directed below the bottom of the hood 32 with the upper portion of the beam obtained from the bottom of the slot and the lower portion of the beam from the top of the slot to avoid having the light blocked off by the hood. It is also desirable to obtain the so-called hot spot light from the central portion of the slot, that is, the portion located adjacent the transverse center of the slot which is closest to the center of the reflector since the images from this portion of the reflector are of minimum vertical depth, and to obtain the light of maximum horizontal spread from portions of the slot adjoining the central portion so that this light will not be blocked off by the sides of the hood 32 near the shield 8.

As heretofore mentioned, the bottom edges (both front and sides) of the hood 32 and the bottom edge of the window slot 30 are in a plane inclined approximately 1° to the horizontal. This bottom edge of the slot 30 is straight but the upper edge is formed in several steps to thereby provide portions which differ in vertical extent. Although all portions of the slot constitute a single continuous opening in the shield 8, the slot has been diagrammatically represented in Figure 6 as composed of separate openings or portions identified by the letters A to J, inclusive, in order to set forth the relation thereof to certain refracting surfaces on the lens 6.

Referring now to the construction of the lens 6, refracting surfaces are provided on the portion of the lens opposite and adjacent the slot 30 of the shield 8. The desired vertical beam spread is obtained primarily by a single horizontal convex flute 36 on the outer face of the lens and the desired horizontal beam spread is obtained by a plurality of vertical convex flutes A' to J', inclusive, on the inner face of the lens.

As shown in Figures 1 and 4, the major portion of the shield 8 may be spaced from the front face of the lens 6 but the portion of the shield adjacent the slot 30 is offset from the rest of the shield and so formed as to fit closely against the horizontal flute 36 on the lens so that there will be minimum space between the edges of the slot and the lens. An opening 38 is provided in the shield for drainage of any moisture or foreign material which may accumulate in the space between the shield and lens, and to prevent the emission of any light rays through this drain opening the portion of the outer face and marginal portion 16 of the lens below the flute 36 may be provided with a light impervious coating of black paint as indicated at 40 in Figure 2 or otherwise shielded to render the same opaque.

The general curvature of the horizontal flute 36 is such that light rays passing through the upper portions of the slot 30 will be directed downwardly to a greater extent than rays passing through the lower portions of the slot whereby the top of the beam pattern will be obtained from the bottom of the slot and the bottom of the beam pattern from the top of the slot to avoid interference with the hood 32. On reference to Figure 4 it will also be seen that the vertical curvature of the flute 36 is formed on two different radii with the upper portion of the flute above the horizontal level diagrammatically indicated at 1 formed on a radius r' which is shorter than the radius r of the portion of the flute below this level to increase the extent of downward deflection and vertical spread

of those light rays that pass through the extreme upper portions of the slot 30.

The vertical beam spread is also dependent upon the vertical extent of the several portions of the slot 30 and the normal vertical spread of the horizontal flute 36 is also modified by the vertical curvature of the flutes A' to J', inclusive, on the inner face of the lens, which curvature varies on different flutes to obtain the desired vertical spread of the several areas of the beam pattern. As shown in Figure 5, the convex curvature of the different vertical flutes on the inner face of the lens is also not uniform but is designed to produce different extents of horizontal spread for different areas of the beam pattern as will be described hereinafter.

Referring now to Figures 5 and 6 which show the beam pattern and the relation of the several portions of the slot 30 and the inner flutes associated therewith to the respective areas of the beam pattern, it will be seen that the flutes A' to J', inclusive, provide blocks of light which superimpose upon one another to build up the beam pattern which is entirely below the horizontal as indicated by line X—X with the several areas symmetrically disposed with reference to the vertical center indicated by line Y—Y.

The center vertical flutes D', E', F' and corresponding portions D, E, F of the slot 30 provide the beam pattern area indicated at d which is of minimum vertical and horizontal spread and constitutes the so-called hot spot. The extent of horizontal beam spread is dependent upon the amount of convexity of these vertical flutes and the extent of vertical beam spread is dependent upon both the vertical depth of the respective slot portions and the relative vertical curvatures of the outer horizontal flute 36 and the inner flutes D', E', F'. On reference to Figure 4 it will be noted that the vertical curvature of these particular inner flutes is substantially the same as that of the outer flute so as to cancel out the vertical spread of the outer flute to provide minimum vertical spread of the hot spot area d. It should perhaps be pointed out that the vertical curvature of all of the inner flutes is effective in modifying the vertical beam spread of the outer horizontal flute only with reference to those portions of the inner flutes which are in substantially horizontal alignment with the slot 30 and the other portions of the inner flutes are shown as vertically curved because the formation of these flutes is facilitated by machining this form on the plunger used for manufacture of the lens.

In the present embodiment which is in commercial use the hot spot area d has a horizontal spread of about 24° and a vertical spread of about 2° with the top of this area about 1° below the horizontal. The rest of the beam pattern is made up of areas which all have their upper limit about 1.5° below the horizontal but vary in vertical and horizontal spreads as will be noted hereinafter.

The beam pattern area indicated at g has substantially the same vertical and horizontal spread as the hot spot area d and is obtained from slot portion G and inner flute G' which are similar to each of the slot portions D, E, F and flutes D', E', F' except for a slight difference in the vertical curvature which is such that the entire area g is positioned about $.5^\circ$ lower than area d. The area indicated at a is obtained from slot portions A, J at opposite ends of the slot 30 and the inner flutes A', J' associated there-

with which have substantially no vertical curvature so that the outer flute 36 provides a greater vertical spread for area *a* than that of areas *d* and *g* heretofore described. The vertical spread of area *a* is about 3° and the amount of convexity of flutes A', J' is such as to provide a horizontal spread of about 46°.

The flutes B', C', H', I' are similar to flutes A', J' with reference to the absence of any appreciable vertical curvature but the vertical depths of the slot portions associated therewith are increased to provide greater vertical beam spreads and the amount of convexity of such flutes also varies to provide greater horizontal spreads of the respective areas of the beam pattern. The flutes I' and B' both provide a horizontal spread of the respective areas *i* and *b* of about 60° but the depths of the associated slot portions I and B are such as to provide a vertical spread of about 4° of area *i* and about 5.5° of area *b*.

The flutes H' and C' both provide a horizontal spread of the respective areas *h* and *c* of about 80°. The slot portions H and C are of such vertical extent that the upper ends thereof extend above the level indicated at *l* in Figure 4 to thereby expose respective portions of the outer flute surface above this level which has been heretofore described as being formed on a shorter radius than the flute surface below this level to thereby provide a substantial increase in vertical spread of areas *h* and *c* as compared to the other areas. The vertical spread of area *h* is about 7.5° and the increased vertical extent of slot portion C provides a vertical spread of about 10.5° for area *c*.

As has been described above, the series of vertical inner flutes A' to J', inclusive, are so formed and associated with the respective slot portions A to J, inclusive, and the outer horizontal flute as to produce the desired beam pattern. The inner flutes are preferably convex as shown and described instead of concave to obtain the desired horizontal spread of the several beam areas in order to prevent light rays from one flute passing through the slot portions which are associated with adjacent flutes. To prevent uncontrolled light rays from passing through the end slot portions A and J, a vertical convex flute M is provided adjacent each of the flutes A' and J' as shown particularly in Figure 5 to converge the light rays adjacent the flutes A' and J' so that they will be intercepted by the shield 8.

Although it might be possible to obtain both vertical and horizontal beam spreads from compound flutes on only one face of the lens, the present arrangement wherein a single horizontal flute on the outer face of the lens is associated with the plurality of inner flutes facilitates the manufacture of the lens and provides a more accurate control of the light rays to produce the desired beam pattern which will be smoothly graduated so that the illuminated roadway appears to be of substantially uniform brightness from the bottom of the beam to the top of the beam.

Although only a single embodiment of the pres-

ent invention has been disclosed herein it will be apparent that the several features thereof may be separately employed in other embodiments and many changes will occur to those skilled in the art and are contemplated as within the scope of the invention and covered by the claims appended hereto.

We claim:

1. In a blackout headlamp for vehicles, the combination with a reflector and light bulb, of a lens having a plurality of vertical flutes, a shield in front of said lens, and a relatively narrow horizontal slot in said shield in line with said vertical flutes, said slot being of irregular contour and having portions thereof in line with some of said flutes of different vertical extent than portions thereof which are in line with other flutes.
2. In a blackout headlamp for vehicles, the combination with a reflector and light bulb, of a lens having a horizontal flute with portions thereof formed on different radii, a shield in front of said lens, said shield having a portion thereof formed to engage said horizontal flute and a relatively narrow horizontal light transmitting slot in the flute engaging portion of said shield.
3. In a blackout headlamp for vehicles, the combination with a reflector and light bulb, of a lens having a horizontal flute with portions thereof formed on different radii, a shield in front of said lens, and a relatively narrow horizontal light transmitting slot in said shield, said slot having the major part thereof in line with the portion of said flute formed on one radius with parts of said slot extended vertically above said major part to expose portions of said flute formed on a different radius.
4. In a blackout headlamp for vehicles, the combination with a reflector and light bulb, of a lens having a plurality of vertical convex flutes, a shield in front of said lens, and a relatively narrow horizontal slot in said shield adapted to expose portions of said flutes, said slot being of irregular contour with a straight bottom edge and a stepped upper edge to provide slot portions of different vertical extents in line with certain of said flutes.
5. In a blackout headlamp for vehicles, the combination with a reflector and light bulb, of a lens, a shield in front of said lens, a relatively narrow horizontal light transmitting slot in said shield having the central portion thereof of less vertical extent than the end portions thereof, and refracting surfaces on said lens in line with said slot including a horizontal flute on the outer face of said lens and a plurality of vertical flutes on the inner face of said lens, said vertical flutes having different radii with the flutes of longer radii in line with the central portion of said slot whereby light rays passing through this slot portion will produce a hot spot area of minimum vertical and horizontal spread and light rays passing through other portions of said slot will produce beam areas of greater vertical and horizontal spreads.
